CLAIM

The ornamental design for a foldable support frame for use when fitting a patient for a cast, as shown and described.

DESCRIPTION

FIG. 1 is a perspective view of a foldable support frame for use when fitting a patient for a cast showing our new design.

FIG. 2 is a front elevational view thereof.

FIG. 3 is a rear elevational view thereof.

FIG. 4 is a top plan view thereof taken along line 4—4 of FIG. 2.

FIG. 5 is a bottom plan view thereof taken along line 5—5 of FIG. 2.

FIG. 6 is a left side elevational view thereof taken along line 6—6 of FIG. 2.

FIG. 7 is a right side elevational view thereof taken along line 7—7 of FIG. 2.
